BICYCLE LOCK

Shigeru Kawakami, 17-3 Higashi Shinkoiwa, 6-chome,
Katsushika-ku, Tokyo, Japan

Filed May 21, 1975, Ser. No. 579,673

Term of patent 14 years

Int. Cl. D8—07

U.S. Cl. D8—113

FIG. 1

FIG. 2

FIG. 3

FIG. 1 is a perspective view of my novel design of a bicycle lock;

FIG. 2 is another perspective view thereof; and

FIG. 3 is a perspective view similar to FIG. 1, but showing the lock open and a chain mounted thereon.

I claim:

The ornamental design for a bicycle lock, as shown and described.
